(57) **CLAIM**

The ornamental design for a vehicle body, as shown and described.

DESCRIPTION

FIG. 1 is a front perspective view of a vehicle body showing my new design;

FIG. 2 is a left side elevation view thereof, the right side being a mirror image of that shown; and,

FIG. 3 is a rear perspective view thereof.

In the drawing views, the tires, emblems, antenna and wheels shown in broken lines are for illustrative purposes only and form no part of the claimed design.
